UNITED STATES PATENT OFFICE.

FREDERICK H. LUENSE, OF STAPLETON, NEW YORK, ASSIGNOR TO AIRCRAFT PROPELLER CORPORATION, OF NEW YORK, N. Y., A CORPORATION OF NEW YORK.

HOLLOW METAL PROPELLER.

1,372,076.

Specification of Letters Patent.

Patented Mar. 22, 1921.

Application filed September 15, 1916. Serial No. 120,214.

To all whom it may concern:

Be it known that I, FREDERICK H. LUENSE, a subject of the Emperor of Germany, residing at Stapleton, county of Richmond, 5 city and State of New York, have invented certain new and useful Improvements in Hollow Metal Propellers, of which the following is a specification.

My invention relates to propellers and has 10 special reference to such as are adapted for aviation service.

One object of my invention is to provide a propeller that shall be sufficiently light and strong for aviation purposes, formed of 15 stamped or die-formed sheet metal sections which can be produced in large quantities at small expense, and that shall not be subject to warping or coming apart under adverse service or climatic conditions. I prefer to 20 use drawn sheet metal such as steel, phosphor bronze, and the like, but any suitable material may be employed, the sections being brazed or welded together at their meeting edges by any of the approved methods 25 in use.

To attain the aforesaid objective results I divide the propeller into such sections as 30 permit the use of dies for forming them and do not impair the strength of the resultant propeller at any vital point. The sections 35 are joined in such manner that the operating characteristics of the propeller are not disturbed or altered by protruding seams and the structure is not distorted by the forces obtaining in flight.

Preferably, the sections are arranged to 40 form a hollow propeller construction and a block of wood is inserted to fill the central portion or hub of the propeller and extends 45 partially within the hollow interior of the blades, thereby relieving the hollow propeller hub of the crushing strains due to the shaft fastening bolts, and counteracting the gyroscopic and other strains induced in flight.

Other objects and advantages of my invention will be set forth hereinafter, and in order that my invention may be thoroughly understood I will now proceed to describe 50 the same in the following specification, and will then point out the novel features thereof in appended claims.

Referring to the drawings:

Figure 1 is a face elevation of a propeller 55 constructed in accordance with my inven-

tion, and constituting one embodiment thereof.

Fig. 2 is a side elevation of the same structure.

Fig. 3 is a perspective view of one section 60 of the propeller blade.

Fig. 4 is a perspective view of the other section of the propeller blade.

Figs. 5, 6, 7 and 8 are sections respectively on the lines 5—5, 6—6, 7—7 and 8—8 of 65 Fig. 1; and

Fig. 9 is a detail hub view of a propeller having three blades and constituting another embodiment of my invention.

Referring to Figs. 1 to 8 inclusive, the 70 two-blade propeller here shown is formed of four sections, each of which extends from the central hub portion of the propeller to the tip of one blade. As shown in Figs. 3 and 4, each blade is comprised of two sections 75 1, 2, of which the edge 3 on one side of section 1 abuts the edge 4 on the opposing edge of section 2, whereas the edge 5 of the other side of section 1 abuts the opposing edge 6 of section 2. The sections comprising the other blade are duplicates respectively of said sections 1, 2, and the blades are alike for either the two blade type of 80 propeller as shown in Figs. 1 and 2, or the three blade type of Fig. 9. 85

Preferably, the abutting edges between sections and between blades are welded together either electrically or by means of the oxy-hydrogen or oxy-acetylene blowpipe, or the like but they may be brazed or joined 90 in some other suitable manner. In the two blade type as indicated in Fig. 1, the central parts of the portions 11, 12 of sections 1, 2 are semicircular in contour and the central portions 13, 14, 15 of the three blade type, 95 as indicated in Fig. 9, are equal sectors corresponding to the number of blades. This will be true if more than three blades are employed.

A set of holes 17 in section 1 and a set of 100 holes 18 in section 2 of the respective blades, are provided for bolts 22 which secure the propeller to the flanges 19 of the sleeve or hub which receives the driving shaft. The central portions of the respective propeller 105 blades are provided with an equal number of bolt holes which are preferably distributed uniformly.

The several sections may be made of steel, 110 or phosphor bronze or the like and prefer-

ably formed to the desired shape, under pressure, by dies or tools. The resulting hollow interior of the propeller varies in transverse sectional dimensions as indicated in 5 Figs. 6, 7 and 8. The block of wood 20, and the oppositely placed circular steel reinforcing plates 21, are positioned within the central or hub interior of the propeller, and suitable holes are provided therein for the 10 fastening bolts 24. The block of wood 20 and the plates 21 enable the fastening bolts to be firmly tightened without crushing the structure or distorting the blades, the latter being materially reinforced by the wood 15 block extensions 22 and mutually strengthened against the stresses caused by the gyroscopic forces induced while in flight. Furthermore, it will be noted that each section on each face of the propeller is connected by 20 the bolts 22 and the plates 21 to a section on the same face so that the several blades are also mutually reinforced for this reason and the shape of the propeller is maintained. Preferably the extensions 22 of the wood 25 block 20 project for a considerable distance into the hollow interiors of the respective blades, the central opening 23 in the block 20 being in alinement with the shaft opening of the propeller and arranged to receive 30 the propeller hub. My invention is not restricted to the use of wood as a reinforcing body at the center, and other suitable materials may be substituted if desired.

As will be observed from the drawings, 35 the propeller is divided into such sections as may be easily formed into the requisite shape, by dies or tools, to wit, each single blade is divided into two sections, one section comprising the front face of the blade and 40 the other section the rear face of the blade, the dividing line running along the leading and trailing edges from the center to the top.

The structure also results in the formation 45 of a hub portion for each blade of suitable construction for fastening to the flanged propeller hub. The sheet steel construction enables me to reduce to a minimum the harmful head resistance of the leading edges of the blades as well as providing the most 50 efficient form for the trailing edges. Furthermore, the propeller of my invention lends itself readily to grinding, polishing, plating or galvanizing, and will maintain its shape under all conditions of active 55 service.

As will be understood, the invention may be embodied in propellers having two or more blades, and various modifications may be effected within the spirit and scope of my 60 invention.

I claim.

1. A propeller composed of die-formed sheet steel sections joined to form a unitary propeller structure and having their joining

edges extending along the leading and trailing edges of the propeller blade and a sheet metal reinforcing plate secured to the propeller structure at the hub. 65

2. A propeller composed of die-formed sheet metal sections joined to form a unitary propeller structure and having their joining edges extending along the leading and trailing edges of the propeller blade said meeting edges being brazed or welded together and a solid reinforcing member at the hub extending 70 for a considerable distance into the hollow blade. 75

3. A propeller composed of sheet metal blades brazed or welded together at the hub and reinforced by a flat circular sheet-metal hub plate. 80

4. A propeller composed of two or more blades, each blade being formed of sections, reinforcing oppositely disposed central steel plates, said plates being provided with bolt 85 holes corresponding to holes in the central portions of each blade section and bolts passing through corresponding holes connecting the respective plates with like faces of the blades. 90

5. A propeller composed of blades brazed or welded together at the center and reinforced by two oppositely disposed central steel plates, said plates being provided with bolt holes corresponding to holes in the central part of each blade, and bolts passing 95 through corresponding holes connecting the respective plates with like faces of the blades. 95

6. A propeller composed of two or more hollow blades and a central block of wood 100 shaped to fit the hollow central portions of the propeller blades and extending partially into the hollow interiors of said blades.

7. The combination with a propeller flange, of die-formed sections welded or 105 brazed together at the leading and trailing edges, joined together at the center as sectors of the circle constituting the hub of the propeller, two reinforcing steel plates at the center, a block of wood shaped in conformity 110 to the hollow interior of the propeller disposed at the center and bolts traversing the blades, the reinforcing plates, the wood block and propeller flange.

8. A hollow metal propeller comprising 115 shaped surface plates joined to form a unitary propeller structure having a hollow hub, and a reinforcing member within the hub and extending for a considerable distance into the hollow blade. 120

9. A hollow metal propeller comprising shaped surface plates joined to form a unitary propeller structure having a hollow hub, and a solid reinforcing block within the hub having projections extending into 125 the hollow blades. 125

10. A hollow metal propeller comprising shaped surface plates joined to form a uni-

tary propeller structure having a hollow hub and a block of wood within the hollow propeller at the hub.

11. A hollow metal propeller comprising 5 shaped surface plates joined to form a unitary propeller structure having a hollow hub and a block of wood within the hollow pro-

peller at the hub and having projections extending for a considerable distance into the hollow blades.

In testimony whereof I have signed this specification.

FREDERICK H. LUENSE.
